ARRANGEMENT IN OR RELATING TO
MUSICAL BOXES
Fritz Koch, 26 Brettnacherstrasse, Berlin-Zehlendorf,
Germany
Filed June 17, 1958, Ser. No. 742,620
11 Claims. (Cl. 46—232)

This invention relates to an arrangement in connection with mechanically operated dancing doll toys and especially but not exclusively to an arrangement in or relating to musical boxes, by means of which arrangement one or more figures are moved on a non-ferromagnetic supporting surface along predetermined paths.

One of the principal features and objects of the present invention is to provide a musical box with dancing figures in which the transmission of movement from a driving part to the figures is effected in such a manner that it is not visible to the spectator. With this object in view the invention provides the figures on a supporting surface constituting the plane of movement and the driving part controlled by the mechanism of the musical box or a motor below said plane of movement, the transmission of movement from the driving part to the figures being effected by permanent magnets.

A further object of the present invention is to provide a musical box in which permanent guiding magnets are arranged on the driving part and guided magnets on the figures respectively so that the figures adjust themselves when moving on the supporting surface as to face always a predetermined direction, without any corresponding change in direction or turning of the guiding magnets below the supporting surface being necessary. With this object the invention provides for poling the permanent guiding magnets arranged on the driving part in substantially vertical direction and for the arrangement of a permanent guided magnet in the base of the respective figure so that the places where the greatest magnetic flux passes out are located laterally side by side. This can be attained either in that the guided magnet arranged in the base of the figure has a horizontal magnetic polarity or it may have a vertical magnet polarity in which case a pole shoe is arranged on the magnet and extends from the top towards the side and then preferably downwardly. By this means the guided magnet of the figure is so attracted that it is drawn along by the guiding magnet and always adjusts itself in the direction of movement, whereas by turning the guiding magnet about its vertical magnetic axis it exerts no moving influence on the magnet of the figure.

Another object of the invention is to provide a musical box on which two or more figures carry out coordinated movements, such as dancing movements.

Yet another object of the invention is the provision of means which bring the movements of the figures into conformity with the rhythm of the music of the musical box.

Still another object of the invention is to provide a musical box in which the figures are guided over the supporting surface optionally straight ahead along predetermined paths, turning to the right and the left and with turnabout movements.

The arrangement according to the invention for moving the figures on the supporting surface can be used not only in conjunction with a musical box but also in conjunction with other mechanical, electrical or manually driven apparatus, such as in conjunction with a phonograph.

Other objects and details of the invention will become apparent from the following description of several

2

preferred forms of construction illustrated by way of example in the accompanying drawings in which:

FIG. 1 is a vertical sectional view through a musical box;

5 FIGS. 2 and 3 show on a larger scale cooperating guiding and guided magnets in various positions;

FIG. 4 shows an arrangement with several similarly moving top figures each provided with a guided magnet cooperating with a guiding magnet;

10 FIG. 5 is a perspective view showing two figures with different magnets and different guiding magnets cooperating therewith to obtain by moving said guiding magnets in the same manner different movements of the figure magnets and their figures;

15 FIGS. 6 and 7 are perspective views of musical boxes with figures movable in time with the music, parts of the housings being broken away.

In the drawings similar parts are designated by the same reference numerals.

20 According to FIG. 1, a mechanical music producing mechanism 2 is accommodated in the housing 1 of a musical box and has a vertical shaft 3 carrying a driving part 4. This driving part 4 is rotated by the shaft 3 and carries permanent driving or guiding magnets 5 and 6

25 which move just below the underside of a non-ferromagnetic supporting surface 7 formed by the top of the musical box. Figures 8 and 9 stand on the supporting surface 7 and each has a convex base 10 in which permanent magnets or soft iron parts are arranged. By the mechanism

30 of the mechanical music producing mechanism 2 the figures 8 and 9 are moved by the magnetic forces on the supporting surface 7 along the paths which are determined by the movements of the driving or guiding magnets 5 and 6. In the form of construction illustrated

35 in FIG. 1 a circular movement is produced. By suitable arrangements of gears or guides any other paths of movement can be obtained.

FIGS. 2 and 3 show possible arrangements of magnets by which a continuous frontal movement of the figures is ensured. A guiding magnet 12 is rigidly connected with

40 a driving part 11 and movable just below a supporting surface 13. The guiding magnet 12 has a magnetic axis extending vertically, that is at right angles to the supporting surface 13. In the embodiment shown in FIG. 2, a

45 figure 14 stands on the supporting surface 13 and has a base in which a permanent magnet 15 is arranged. This magnet 15 has a magnetic axis extending horizontally, that is parallel to the supporting surface 13. By the attraction of unlike poles the magnet 15 will always be

50 drawn along by the movement of the guiding magnet 12, with the result that the point designated by 16 will always face in the direction in which the figure 14 moves.

According to FIG. 3 the base carrying a figure 14¹ is equipped with a permanent magnet 15¹ which has a

55 vertical polarity similar to its guiding magnet 12. The component defining the front direction is, in this form of construction, formed by a laterally extended pole shoe 17 of ferromagnetic material in the shape of a hook pointing towards the supporting surface 13. This pole shoe 17

60 with the upper pole of the guiding magnet 12 of like polarity produces repulsion so that the pole shoe 17 is always located behind in the direction of movement. In FIGS. 2 and 3 the direction of movement is indicated by arrows I.

65 According to FIG. 4 three guiding magnets 12 are fixed in line on a common guide or driving part 18. To each of said magnets 12 a magnet 15¹ is coordinated which is located in the base of a figure 14² which is movable over the supporting surface 13. The magnets 15¹ are of the

70 same construction as the magnet 15¹ shown in FIG. 3. However, instead of the magnets 15¹ magnets 15 shown in FIG. 2 may also be used. Any movement of the driv-

ing part 18 below the supporting surface 13 produces a simultaneous movement of the figures 14² similarly timed and in the same frontal directions. In this manner precise turning movements can be attained, with the result that even groups composed of any desired number of figures will carry out simultaneous and synchronous movements like drilling or ballet-dancing. It is evident that instead of three figures, each with a guiding magnet 12 as illustrated in FIG. 4, any number of figures each with a guiding magnet may be provided.

FIG. 5 shows arranged below the supporting surface 13 a driving part 18 carrying guiding magnets 12 and 12¹. Two figures 14¹ and 14³ representing a beetle and a bird are placed on the supporting surface 13 for movement thereon. The toy figure 14¹ representing the beetle is carried by a magnet 15¹ which cooperates with the magnet 12 and moves on the supporting surface 13 as has already been described in connection with FIG. 3. The toy figure 14³ representing the bird is carried by a magnet 15² which cooperates with the magnet 12¹. The magnets 15² and 12¹ have their magnetic axes extending horizontally and due to this the figure magnet 15² can only move in the same manner as its guiding magnet 12¹ does. The figure magnet 15² has a convex or curved base which effects that the toy figure when being moved ahead tips forwardly and when being moved backwardly tips backwardly. Thus two different kinds of movement are attained on the supporting surface 13 by a single kind of movement of the driving part 18 below the supporting surface 13 which results in very amusing and surprising effects.

FIG. 6 shows a musical box in which the movements of the figures are adapted to the rhythm of the music. In this form of construction a driving part 4¹ is moved by the shaft 3 of the mechanical music producing mechanism 2 and carries intermeshing gear wheels 21 and 22 rotatable about vertical axles 19 and 20 respectively. The arrangement is such that the teeth of the gear wheels 21 and 22 actually most remote from the shaft 3 have the same distance from said shaft 3 and due to this lie on the same circle. Several stationary teeth 24 are fixed at certain distances apart on this circle in the housing 1 and mesh with the gear wheel 21 or with the gear wheel 22 as these gear wheels move past, thereby causing them to turn each time through a predetermined angle. This turning movement is always transmitted from one gear wheel to the other so that each gear wheel carries out a forward and backward movement. The gear wheel 22 carries two guiding magnets 12. Two figures 25 and 26 coordinated to the two magnets 12 are arranged on the supporting surface 7 of the musical box serving as plane of movement and carry in their bases permanent magnets 27 and 28 respectively. In the form of construction illustrated in FIG. 6, the magnet 27 is constructed similarly to the magnet 15¹ in FIG. 3, whereas the magnet 28 has only the same vertical magnetic polarity as its guiding magnet 28.

FIG. 7 shows the whole arrangement illustrated in FIG. 6 accommodated in a housing constructed in the form of a dancing stage. This housing consists of a rigid structure 29 made from wood, plastic material or the like and forming frames for top, bottom and side walls. At least the bottom and the side walls consist of sheets of veneer having a thickness of about 1/2 mm. It is evident that the top wall constituting the supporting surface or plane of movement for the dancing figures may also consist of a sheet of veneer which is preferably smoothed or covered with any suitable material which improves the sliding and turning movements of the figure magnets guided over the supporting surface. However, a supporting surface consisting of glass has proved most favorable in practice. Experiments have shown that by a housing constructed in the manner described above, the effect of sound of the music producing mechanism is considerably improved.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description and all changes which come within the meaning and range of equivalency of the claims are therefore intended to be embraced therein.

10 I claim:

1. In an amusement device, a non-ferromagnetic horizontal support surface, power mechanism including a vertical drive shaft below said surface, magnetically attracted figures supported for free movement on said support surface, a driving part fixed to said vertical drive shaft and rotatable about an axis of rotation defined by said drive shaft, at least one gear wheel rotatably mounted on said driving part with its axis parallel to the axis of rotation defined by said drive shaft, spaced permanent magnets on said gear wheel, said permanent magnets cooperating with said magnetically attracted figures for driving the same, and abutment means intermittently engageable with said gear wheel whereby the figures on said supporting surface are moved in a first path of movement due to rotation of said driving part and a second intermittent path of movement due to engagement of said abutment means engaging said gear wheel.
2. The structure of claim 1 in which one of said spaced permanent magnet means has a magnetic axis normal to the plane of movement of said figures on said supporting surface.
3. The structure of claim 1 in which said power mechanism comprises a music producing mechanism.
4. The structure of claim 1 in which said abutment means comprises stationary teeth concentric to the axis of rotation of said drive shaft.
5. The structure of claim 1 including force-transmitting means on said driving part engageable with said gear wheel and abutment means for providing an intermittent reverse rotation to said gear wheel opposite that caused by the engagement of said gear wheel and abutment means.
6. The structure of claim 5 in which said force-transmitting means comprises a second gear wheel meshed with said first mentioned gear wheel, the axes of said gear wheels each being on a circle concentric to the axis of rotation of said vertical shaft, said abutment means comprising stationary teeth concentric to said axis of rotation of said vertical shaft and intermittently engageable with said gear wheels for causing rotation of said spaced permanent magnets in clockwise direction and in counterclockwise direction, respectively, about the axis of said wheel gear.
7. The structure of claim 3 in which said power mechanism comprises a music producing mechanism, the rhythm of said music producing mechanism being synchronized with the movement of said spaced permanent magnets by arranging said abutments on said circle so that said magnetically attracted figures are moved in said first and second path of movement chronologically in time with the music produced by said music producing mechanism.
8. An arrangement as set forth in claim 2, wherein said figures include bases having permanent magnets of horizontal polarity.
9. An arrangement as set forth in claim 2, wherein said figures include bases having permanent magnets of vertical polarity and carry a pole shoe extending laterally from the upper pole.
10. An arrangement as set forth in claim 2, wherein said figures include bases having permanent magnets of vertical polarity and carry a laterally extended pole shoe of ferromagnetic material in the shape of a hook pointing towards said supporting face.
11. An arrangement set forth in claim 3, wherein

means are provided for rotating the figure driving means in time with the music produced by the musical box.
